Des. 200,387
Patented Feb. 16, 1965

200,387

LAWN SPRINKLER

Clarence Lee Folden, Downers Grove, Ill., assignor to
Sears, Roebuck & Co., Chicago, Ill., a corporation of
New York

Filed Nov. 13, 1962, Ser. No. 72,477

Term of patent 14 years

(Cl. D91—1)

FIGURE 1 is a perspective view of a lawn sprinkler showing my new design;

FIGURE 2 is a rear end elevational view thereof;

FIGURE 3 is a side elevational view thereof; and

FIGURE 4 is a top plan view thereof.

The dominant features of my design reside in the portions shown in solid lines.

I claim:

The ornamental design for a lawn sprinkler, as shown and described.
